Inventor;
John B. Wentworth,

UNITED STATES PATENT OFFICE.

J. B. WENTWORTH, OF LYNN, MASSACHUSETTS.

LEATHER-SHAVING KNIFE.

Specification of Letters Patent No. 20,911, dated July 13, 1858.

To all whom it may concern:

Be it known that I, JOHN B. WENTWORTH, of Lynn, in the county of Essex and Commonwealth of Massachusetts, have invented 5 a new and useful Improvement in Leather-Shaving Knives; and I do hereby declare that the following is a full, clear, and exact description of the construction and operation of the same, reference being had to the 10 accompanying drawings, forming a part of this specification, in which—

Figure 1 is a perspective view of the instrument ready for use; Fig. 2 is a view of the blade removed from the stock; Fig. 3 is 15 an outside view of one half of the stock; Fig. 4 is an inside view of the other half of the stock; and Fig. 5 is a section of the smaller end of handle, B.

Like parts are indicated by the same letters in all the drawings.

To enable others skilled in the art to make and use my invention, I will now describe its construction and operation.

A is a wooden handle, on a line with the 25 stock, and shaped like those in common use. B is the cross handle, attached to the other end of the stock in the usual manner, but of a new and peculiar shape so as to fit the hand and act as a brace upon the lower edge 30 of the same, and also upon the thumb, to enable a person to carry the knife level and at once perceive its exact position in forcing it down upon the leather. The middle of this handle is convex, while the lower part, 35 at 1, is concave, and terminated with a bulge, or knob, at 2, to rest against the edge of the hand. The other end of the handle, as seen in Fig. 1, is made smaller to arch the thumb, and is also provided with depressions, b, 40 (see Figs. 1 and 5) for the ball of the thumb, whereby the implement is braced and prevented from rocking in the hand.

C C (Fig. 1,) is the stock made in two parts; an outside view of one half being 45 seen in Fig. 3, and an inside view of the other half in Fig. 4. These halves are made of steel, and, as will be seen in Figs. 1 and 3, are beveled from the line α , to γ ; the part between α and γ , being parallel with the 50 inner side. These halves are held together

and confine the blade, D, between them, by means of seven screws which pass through half, C C, and screw into C' C'; two of said screws, f and f, passing through the shanks, and five, e, e, e, e, e, through the unbeveled part of the stock, as shown in Fig. 1. These screws, with the exception of f f (which secure the corners of the blade) are set on a line upon the side, or back, of the stock, and at a distance from the center of the same. 60 Thus the back of the stock, being the heaviest part, acts as a sort of counterbalance to the action of the cutting edge of the blade. The blade, D, being carried horizontally, or level, and the edge cutting at a right angle 65 with it, it is obvious that, by placing the screws at a distance from the center of the stock, the cutting edge of the knife may be very much nearer to a line passing through the center of the handles, A and B, and 70 thereby greatly shorten the leverage of the cutting edge; which is very important, inasmuch as the least cant would injure the skin, or leather.

In the Tomlinson patent, and in all other 75 shaving-knives with which I am acquainted, the heaviest part of the stock is the center, requiring a hard grip and great strength in the arms, to keep it level and free from rocking; whereas this difficulty is effectually 80 obviated in my invention by the counterbalance, and shorter leverage, alluded to above. I also make the bevel more tapering, without widening the stock, or altering the leverage; which constitutes another improve- 85 ment over any other stock extant.

D Fig. 2 is the blade, with slots, d, d, d, d, d, through which pass the screws, e, e, e, e, e, which confine the blade between the two halves of the stock. These slots, as seen in 90 Fig. 2, are about one third as long as a new blade is wide. When a new blade is first put into the stock, the ends of the slots, as seen in Fig. 1, are brought up to the screws, e, from the beveled side, and moved out, as 95 used up. When one side is thus worn up, the blade is taken out and turned so as to use the other side.

I have used a leather shaving knife for more than twenty years, and find that this 100

of mine is much superior to all others, for lightness, safety, and the ease with which it is worked.

What I claim as my invention and desire 5 to secure by Letters Patent, is—

The within described leather shaving knife, consisting of a stock, C C', with a bevel only on one edge, extending beyond

the center from y to z , and provided with screws, e , combined with a blade, D, having 10 slots, d , operating as, and for the purpose specified.

JOHN B. WENTWORTH.
